UNITED STATES PATENT OFFICE.

ROBERT LUNDELL, OF NEW YORK, N. Y., ASSIGNOR OF TWO-THIRDS TO
THE SPRAGUE ELECTRIC COMPANY, OF SAME PLACE.

DESIGN FOR A FRAME FOR ELECTRIC-FAN MOTORS.

SPECIFICATION forming part of Design No. 31,369, dated August 8, 1899.

Application filed July 16, 1898. Serial No. 688,179. Term of patent 14 years.

To all whom it may concern:

Be it known that I, ROBERT LUNDELL, a citizen of the United States, residing at New York, in the county of New York and State of New York, have invented and produced a new and original Design for a Frame for an Electric-Fan Motor, of which the following is a specification, reference being had to the accompanying drawings, forming a part thereof.

Figure 1 is a front elevational view of a frame for an electric-fan motor embodying my design, and Fig. 2 is a side elevational view thereof.

As shown in the drawings, the leading or material features of my design consist of a body part A of the motor of a conformation substantially that of a zone of a sphere, bounded by two parallel end plates B B, said end plates being provided with journal-bear-

ing extensions C C for the shaft of the motor, 20 and the entire frame supported by a standard S of substantially the conformation shown, F being a fan-protecting frame rigidly secured to the top and bottom of the motor-frame and constituting a part of the complete or entire design. 25

Having described my invention, what I claim as new, and desire to secure by Letters Patent of the United States, is—

The design for a frame for an electric-fan 30 motor, substantially as shown and described.

In testimony whereof I have hereunto subscribed my name this 6th day of July, 1898.

ROBERT LUNDELL.
